UNITED STATES PATENT OFFICE

164,588

CHAIN FOR A BRACELET OR THE LIKE

Maurice Moss, New York, N. Y.

Application November 19, 1949, Serial No. 6,160

Term of patent 3½ years

(Cl. D45—4)

To all whom it may concern:

Be it known that I, Maurice Moss, a citizen of the United States of America, residing at New York, in the county and State of New York, have invented a new, original, and ornamental Design for a Chain for a Bracelet or the like, of which the following is a specification, reference being made to the accompanying drawing, forming a part thereof.

Fig. 1 is a top plan view of a chain embodying my new design;

Fig. 2 is an edge view thereof;

Fig. 3 is an enlarged top plan view of one of the links comprising the chain; and

Figs. 4 and 5 are enlarged edge and side views, respectively, of the single link shown in Fig. 3.

I claim:

The ornamental design for a chain for a bracelet or the like, substantially as shown.

MAURICE MOSS.
